(57) **CLAIM**

We claim the ornamental design for a lottery ticket dispenser, as shown and described.

DESCRIPTION

FIG. 1 is a front perspective view of a lottery ticket dispenser according to our new design.

FIG. 2 is a front elevational view thereof;

FIG. 3 is a left side elevational view thereof;

FIG. 4 is a right side elevational view thereof; and,

FIG. 5 is a top plan view thereof.

In the drawings, the broken lines represent portions of the lottery ticket dispenser that form no part of the claimed design.
